UNITED STATES PATENT OFFICE.

CARL F. TROTTNOW, OF ROCK ISLAND, ILLINOIS.

BOTTLE-CAPPING MACHINE.

1,848,973.

Specification of Letters Patent. Patented Aug. 10, 1920.

Application filed April 10, 1919. Serial No. 288,956.

To all whom it may concern:

Be it known that I, CARL F. TROTTNOW, a citizen of the United States, residing at Rock Island, in the county of Rock Island and State of Illinois, have invented certain new and useful Improvements in Bottle-Capping Machines, of which the following is a specification.

My invention has reference to bottle capping machines, for use in supplying the tops of bottles containing beverages of various kinds with metal caps. The chief purpose thereof is to provide a device of that character of simple form, having a minimum number of parts, and which can be cheaply produced.

In the drawings: —

Figure 1 shows my invention in side elevation. Fig. 2 is a detail of the plunger mechanism. Fig. 3 is a detail of the lever 10, in plan view.

1 represents a base; in which is mounted a standard 2, slideable upon which is a cylindrical head 3. Projecting outwardly from the head 3 is a web 4, at the outer end of which is carried a sleeve 5. Vertically slideable in the sleeve 5 is a plunger 6, provided on its lower end with a capping tool 7, on two sides of which are shoulders 8 upon which rest the forks 9 of a hand-lever 10. The ends of the forks are pivotally connected with the lower part of the head 3 by means of a pin 11, passing through such head, and also adapted for engagement with one or other of a series of notches 12 in the side of the standard 2. By removing the pin 11 the head can be adjusted upon the

standard, and held at desired heights thereon. The distance of the capping devices from the base 1 can thus be made to conform to the size of the bottles which are being provided with caps. 40

The plunger 6 and tool 7 are held normally in elevated position by means of a spring 13 between the sleeve 5 and a pin in the upper end of the plunger. 45

The head 3 is also provided on its rear side with a plate 14, which may be fitted with fastening means, such as screws, so that the upper mechanism can be secured directly to a wall or other structure, and the supporting base and standard dispensed with. 50

It will be observed that the pin 11 serves the double purpose of furnishing a supporting means for the head 3 and appurtenant parts, in connection with the notches 12, and also provides the pivotal connection for the lever 10. No other connecting member is used in the machine. 55

What I claim and desire to secure, is: 60

A device of the class described, comprising a suitably mounted standard, provided at its upper end with a series of notches; a head slideable on said standard; a pin removably held in said head and adapted for engagement with said notches; capping mechanism carried by said head, and provided on opposite sides with shoulders; and a bifurcated hand-lever pivotally connected with said pin and having a bearing on said shoulders. 65

In testimony whereof I affix my signature.

CARL F. TROTTNOW.
